UNITED STATES PATENT OFFICE.

JOHN DUNCAN WILLIAMS, OF CHARLOTTE, NORTH CAROLINA.

BASS-DRUM-OPERATING MECHANISM.

1,350,195.

Specification of Letters Patent. Patented Aug. 17, 1920.

Application filed October 7, 1919. Serial No. 329,017.

To all whom it may concern:

Be it known that I, JOHN D. WILLIAMS, a citizen of the United States, residing at Charlotte, in the county of Mecklenburg and

5 State of North Carolina, have invented new and useful Improvements in Bass-Drum-Operating Mechanism, of which the following is a specification.

This invention relates to devices for beating bass drums and has for its object the provision of a manually controlled beating mechanism operable by the operator's striking his hand either upwardly or downwardly upon an arm whereby the drum may be 10 beaten without sounding the cymbals as is the case when the drum is beaten by the ordinary foot pedal.

An important object is the provision of a device of this character which will beat the 20 drum whether the operator strikes the control member from one side or the other, means being provided for returning the striking member to initial position.

Another object is the provision of a device 25 of this character which may be quickly and easily attached to the supporting hoops of the drum without injury thereto.

An additional object is the provision of a device of this character which will be simple 30 and inexpensive in manufacture, highly efficient in use, durable in service, and a general improvement in the art. By a rapid up and down movement of the lever 23, a roll, ranging from a scarcely audible rumble to a 35 thunder imitation may be produced.

With the above and other objects and advantages in view, the invention consists in the details of construction to be hereinafter more fully described and claimed, and illustrated in the accompanying drawings in which:

Figure 1 is a sectional view through a portion of a base drum showing my device thereon in side elevation,

40 Fig. 2 is a plan view,

Fig. 3 is an elevation taken at right angles to Fig. 1,

Fig. 4 is a view similar to Fig. 1, showing the striking member moved into engagement 50 with the drum head by downward movement of the operating lever, and

Fig. 5 is a similar view showing the striking member operated by upward movement of the control lever.

55 Referring more particularly to the drawings, the letter A designates a portion of a

bass drum provided at its edge with the co-operating hoops B and C which serve to clamp the drum head D in position.

In carrying out the invention, I provide a 60 bracket 10 which carries upon one side a clamping member 11 engaging the hoops B and C and provided with an adjusting thumb screw 11 whereby it may be securely clamped.

This bracket 10 includes an arm 12 which extends somewhat toward the center of the drum head and upon the end of which is pivotally mounted, as shown at 13, a striking member 14, carrying at its extremity a soft

65 felt beater head 15 adapted to strike against the drum head D for making the required sound. This striking member 14 is provided adjacent the arm 12 with a lateral extension 16 to which is pivotally connected, as shown at 17, one end of an angular arm 18 having

70 its opposite extremity extended laterally, as shown at 19. Pivotally connected with this lever 18, as shown at 20, is a link 21 which has its other end pivotally connected, as

75 shown at 22, with a hand operating lever 23 which is, in turn, pivotally mounted, as shown at 24, upon the bracket 10. Disposed within the lateral extension 19 on the lever 18 and disposed between the lever 18 and the adjacent end of the striking member 14,

80 are rubber cushions 25 and 26, respectively. Secured at one end to the bracket 10, is a spring 27 which has its intermediate portion provided with a plurality of convolutions and which has its other end connected with

85 the striking member 14, the purpose of this spring being to hold the striking member 14 in such position that the beater head 15 will be held out of engagement with the drum head.

90 95 The operation of the device is as follows:

The parts being constructed and arranged as above described, when the operator strikes his hand upon the lever 23, moving it downwardly, the link 21 will be moved

100 downwardly which will cause the lever 18 to rock upon the cushion 26 as a fulcrum whereupon the striking member 14 will be

105 partially rotated upon its pivot 13 so that the beater head 15 will strike against the drum head D and make a sound. The

spring 27 will then return the parts to original position with the beater head 15 spaced from the drum head. In the event that the

operator strikes his hand upwardly against the lever 23, the link 21 will be moved upwardly which will result in pulling the lever

110

18 bodily upwardly out of engagement with the cushion 26 and this movement will result in identically the same swinging movement of the striking member 14 so that the beater head carried thereby will strike the drum head. It will thus be seen that regardless of which way the operator strikes the operating lever 23, the proper action will be produced to make a sound. It will be noted 10 that the cushion 26 in addition to functioning as a fulcrum for the lever 18 will also serve to reduce the shock and deaden the sound when the lever 18 descends to normal position after being pulled upwardly 15 by the operator striking upwardly upon the lever 23. The cushion 25 also serves to absorb the shock and deaden the sound when the link 21 returns to normal position after the lever 23 is moved by the operator's 20 striking downwardly thereon.

From the foregoing description and a study of the drawings it will be apparent that I have thus provided an extremely simple device which may be readily attached to 25 a bass drum and by means of which the drum may be manually operated either by an upward or downward movement of the operator's hand.

While I have shown and described the 30 preferred embodiment of my invention it is of course to be understood that I reserve the right to make such changes in the form, construction, and arrangement of parts as will not depart from the spirit of the invention 35 or the scope of the subjoined claims.

Having thus described my invention, I claim:

1. A device of the character described 40 comprising a bracket detachably engageable upon the hoops at one end of a bass drum, a striking member pivotally connected with said bracket and carrying a beater head adapted to be moved into engagement with the head of the drum, a lateral extension on 45 said striking member, a lever pivotally con-

nected with said lateral extension at one side of the pivot point of the striking member, a link pivotally connected with said lever at the opposite side of the pivot point of said striking member, and an operating lever 50 pivoted upon said bracket and pivotally connected with said link.

2. A device of the character described comprising a bracket detachably engageable upon the hoops at one end of a base drum, a striking member pivotally connected with said bracket and carrying a beater head adapted to be moved into engagement with the head of the drum, a lateral extension on said striking member, a lever pivotally 60 connected with said lateral extension at one side of the pivot point of the striking member, a link pivotally connected with said lever at the opposite side of the pivot point of said striking member, an operating lever 65 pivoted upon said bracket and pivotally connected with said link, and a cushion disposed between said first named lever and said striking member and serving as a fulcrum for said first named lever when said operating lever is depressed.

3. A bass drum attachment comprising a bracket provided with means for detachable engagement upon a base drum, a pivoted striking member carried by said bracket and 75 carrying a beater head movable into engagement with the head of the drum, means normally holding said striking member with said beater head out of engagement with the drum head, and an operating lever pivoted 80 upon said bracket and connected with said striking member, the connection between said operating lever and said striking member being such that said striking member will be moved to bring the beater head into 85 engagement with the drum head upon movement of said operating lever in either direction.

In testimony whereof I affix my signature.
JOHN DUNCAN WILLIAMS.
